LOCK

Henry B. Moninger, Philadelphia, Pa.

Application August 4, 1936, Serial No. 94,132

11 Claims.

(Cl. 70—341)

This invention relates to improvements in locks and it is particularly useful for pin tumbler cylinder locks having the usual rotatable key plug for withdrawing the customary spring actuated door latch. When the key is inserted in the key plug, the tumblers are operated to "break" position to permit the key plug to be turned and withdraw the latch by means of the roll back arm or cam which is attached to the key plug. One of the objects of the invention is to provide a lock which has self-contained therein, means for securing the lock cylinder in the lock casing. Heretofore the locks have been secured by such means as a screw bolt, which makes unauthorized removal of the lock a relatively simple matter. By my invention it is, for all practical purposes, impossible to effect an unauthorized removal of the lock.

Another object of the invention is to provide the lock, as a self-contained part thereof, with "shut-out" means whereby the lock can be rendered temporarily inoperable by anyone other than the holder of the key by means of which the shut-out is made effective or ineffective.

In the preferred form of my invention, I propose to combine both the improved lock securing means and the shut-out means in a self-contained lock unit.

More specifically, it is an object of my invention to provide a slidable bar or bolt as part of the lock, which bar functions to secure the lock cylinder in the lock casing, preventing the unauthorized removal of the lock; and to provide a "shut-out", which is slidable in the said bar and is movable to a position making it impossible to operate the roll back arm.

The keys employed when the foregoing features are applied to a standard form of key plug, tumbler lock, may be described as follows: First, the key that operates the slidable bar which locks or secures the lock cylinder in the lock casing; second, the key which operates the "shut-out" to prevent the functioning of all other keys otherwise operable; third, the usual guest or change key; and fourth, the usual variety of master keys.

I accomplish the foregoing, together with such other objects and advantages as will hereinafter appear or are incident to my invention, by means of the lock mechanism shown in the accompanying drawings, wherein:

Figure 1 is an elevational view of a portion of the interior of the lock receiving casing or casting, showing the lock cylinder attached thereto and with the locking bar in its protracted posi-

tion, operable to prevent unauthorized removal of the lock from the casing;

Figure 2, a sectional view taken on the line 2—2 of Figure 1;

Figure 3 is an end view showing the "shut-out" block in position to prevent the use of the guest and the usual master keys;

Figure 4 is a view corresponding with Figure 3 but with the roll back arm removed to more clearly show how the "shut-out" block prevents operation of the roll back arm;

Figure 5 is a longitudinal sectional view through the axis of the lock cylinder and key plug, with a guest or change key in place;

Figure 6 is a fragmentary sectional view 15 through the axis showing part of an inserted special key which operates the "shut-out" block, said key having formed at its cam end an additional bit of an elevation to adjust the parts to be operated;

Figure 7 is a fragmentary sectional view 20 through the axis of the lock, showing part of a special key which operates the slidable bar for retaining the lock cylinder in the casing, said key having formed at its cam end, an additional bit of an elevation to adjust the parts to be operated;

Figure 8 is a section taken on the line 8—8 of Figure 5 showing this slidable locking bar in its protracted, operative locking position; 30

Figure 9 is a view corresponding to Figure 8 but showing the "shut-out" block moved to its operative or shut-out position where the usual guest or master keys become inoperative but with the locking bar in its protracted effective 35 locking position.

Figure 10 is a sectional view showing the lock cylinder sliding bar retracted and the special key (in section) which operates the bar, still in place;

Figure 11 is a perspective view of the lock cylinder locking bar;

Figure 12 is a perspective view of the "shut-out" block;

Figure 13 is a perspective view of a duplex 45 pin tumbler carried in the "shut-out" block;

Figure 14 is a sectional view showing the lock cylinder sliding bar of Figure 1 applied to a lock of the sleeve type; and

Figure 15 is a section taken on the line 15—15 50 of Figure 14, but drawn on a smaller scale.

Referring now to the drawings the reference numeral 1 designates the casing member adapted to enclose the lock mechanism, which casing is fitted into an opening in the front edge of the door. 55

The cover for the casing is indicated at 2. The internally threaded opening of the casing is shown at 3 and into this opening the lock cylinder 5 which has external threads 4, is screwed. On the inner portion of the casing 1 are a pair of parallel integral, spaced lugs 6 and 7 adapted to provide a space 8' receiving the end of sliding locking bar 9.

Projecting from the inner end of the lock cylinder 5 is the usual boss or ring 5' encircling the key plug bore 28² (see Figures 2 and 4). Directly above and transecting the top of this ring down to the depth of its inner circumference, is a transverse groove 8 into which the locking bar 9 is adapted to be snugly received. The bottom of the groove 8 provides a substantial support or bearing surface not only for the bar 9 but also for the plate 20 of the "shut-out" block indicated as a whole by the reference numeral 15.

It will be clear from the drawings that when the sliding bar 9 is operated so that its work end enters space 8' between the lugs 6 and 7, it effectively prevents the lock cylinder 5 from being unthreaded and removed from the casing 1.

Reference will now be made to the means by which the bar 9 may be operated. Formed within the bar 9 is a recess 11 (see Figures 8-11 inclusive) and bored through the upper wall of this recess and extending between the surfaces 9' and 10, are two parallel openings or holes 12 and 13, connected laterally by the narrow channel 14 formed by the two oppositely extending projections 14' (see particularly Figure 11).

The "shut-out" block 15 consists of two major portions 19 and 20, the part 19 projecting into and being slidable in the recess 11. The portion 20 moves in the recess 21 formed in the under face of the bar 9 and is of a greater width than the locking bar so that the part 20' of the plate 20 projects laterally from a side face of the bar. Two holes 16 and 17, corresponding to the holes 12 and 13, are bored in the top of the part 19 of the "shut-out" block, these two holes also being connected laterally by the narrow channel 18 formed by the projections 18'. These holes 16 and 17 together with the connecting channel 18 open downwardly into an elliptically formed bottomless chamber or recess 38 in the lower part of the portion 19 and the plate 20 (see particularly Figure 9). This elliptical recess houses the duplex pin tumbler 22 shown in Figure 13, when said tumbler is normally at rest upon the upper end of the special pin tumbler 37 (see Figures 8 and 5). The recess 38 also provides room in the base of block 15 for the upward entrance of this pin tumbler when it is caused to lift and displace the duplex pin tumbler 22 (see Figure 10).

The duplex pin tumbler has two cylindrically formed parts or pin sections 23 and 24 connected by the neck 25. This tumbler is normally carried in the block 15 and when the holes 16 and 17 are in registry with the holes 12 and 13, the duplex pin tumbler may be moved to lock the bar 9 and the shut-out block together. The bottom of the pin tumbler is formed into a concave surface 26 which contacts with the upper convexed end of the special pin tumbler 37, located in the chamber 28' of the key plug 28.

The usual roll back arm 27 is attached to the end of the key plug 28 by means of the screws 29. This arm operates the usual latch bolt 29² by its engagement with the arm 29'. Secured to the roll back arm is a pin or stud 30 the purpose of which is to engage the projecting portion 20' of the plate 20 of the shut-out block when the shut-out block 15 is in its operative or shutting-out posi-

tion as shown in Figures 3, 4 and 9. When this occurs the roll back arm is held and can no longer engage and retract the part 29' of the latch bolt 29², thus forestalling an attempt to operate the lock unauthorizedly.

31 designates the tumbler chambers in the cylinder 5 in which the pin tumblers 32 and the actuating springs 33 are located. 34 are the usual antifriction balls which contact with the bits of the keys. The key plug 28 is formed with the usual pin tumbler openings 35 in which are located the pin tumblers 36. These parts constitute the conventional pin and tumbler construction, with the exception that a slight modification is made in the tumbler chamber 31' and its pin tumbler 47. This pin tumbler 47 is provided with a convex lower end 47' which bears upon the flat upper end of the pin tumbler 36' in the tumbler chamber 35', as shown in Figures 5, 6 and 7. With the orifices of the chambers 31' and 35' registering, the tumbler 47 under the pressure of spring 33' can partly descend from chamber 31' into chamber 35' as shown in Figures 6 and 7, or until it is stopped by contacting with tumbler 36' when the latter is positioned by a bit 47² of either the special key 42 or the key 43, at which time only the convex end of tumbler 47 can enter the orifice of chamber 35'. The parts as so adjusted then become a locating detent by means of which the operator knows when the key 30 is in position to be withdrawn. It will be manifest that when the key plug is rotated, the upper rim 35' (see Fig. 7) will press against the convex end 47' and force tumbler 47 upward until its convex end 47' is bearing on the surface of the key plug 28 and upon which it will then ride. The tumbler 47 operates in the usual way to pin the key plug against rotation within the cylinder. To free the key plug for rotation, insofar as the tumbler 47 is concerned, it is necessary to position said tumbler by means of the bit 36² of the guest or change key 36³ so that either its convex lower end 47' is raised flush with the surface of the key plug (see Figure 5) or its flat upper end is so aligned. The position in either instance depends upon the elevation of this particular bit of the inserted change key.

Formed at the top of the rearmost portion of the key plug bore 28² is a rectangular recess, extending longitudinally forward. Each side of the rectangular recess is indented with a U shaped notch 37' and 37², transversely opposite and in line with the chamber 28', in which is located the pin tumbler 37 (see Figure 8). These notches are of the same width as the diameter of the chamber 28' and of such depth as to permit of the needed arcuate movement of the tumbler 37, when it is used to actuate either the bar 9 or the block 15.

The key plug 28 is provided with the usual key-way 39 having a ledge 40 (see Figures 5 and 6) on which the balls 34 and the pin tumbler 31 normally rest before a key is inserted. 41 is a slidably plate which closes the upper ends of the openings of the tumbler chambers. 45 designates the innermost tumbler chamber of the cylinder 5 in which the retaining pin tumbler 44 and the actuating spring 33² are located. The pin 44 is employed to retain the sliding bar 9 in either a protracted or retracted position; and it further acts to retain the shut-out block in either its operative or its inoperative position.

The operation of the device is as follows:

To condition the unit for screw threading into the lock case, if the parts are not already in the

position of Figure 10, the procedure is as follows: the key 42 is inserted and the bit 42' elevates the tumbler 37 which in turn elevates the duplex pin tumbler 22 until the upper surface of the latter is flush with the top surface of the locking bar, at which time the lower face of tumbler 44 will also be flush with the upper surface of the locking bar. The key can now be turned clockwise looking at the face of the lock, which brings the locking bar, the shutout block and the associated parts to the position shown in Figure 10. The key 42 is now turned counterclockwise until the arresting pressure of the detent tumbler 47 is felt, whereupon the key may be withdrawn. When this occurs the duplex pin tumbler and the pin 44 move downwardly under the influence of the spring 33² and the locking bar and shut-out block will be locked together, with the locking bar in retracted position. The lock may now be screwed in place.

To prevent its unauthorized removal from the door, the key 42 is used and is now turned counterclockwise, looking at the face of the lock. This can be done because when the key is inserted all parts are brought to the break position. This counterclockwise movement causes the locking end of the locking bar to move into the space 8' and also brings the shut-out block to the position shown in Figure 8. The key is now rotated clockwise to middle position, when the detent 47 is felt and the key is withdrawn. The position of the parts is now as represented in Figures 1 and 8. When the key is withdrawn the pin 44 descends sufficiently to lock the bar 9 with respect to the cylinder case and also the shut-out block with respect to the bar 9. In this position it will be seen that the pin 30 clears the projecting portion 20' of the shut-out block and the roll back arm can be swung all around so as to engage the member 29', to pull back the latch. Either the usual guest key or the master key can now be used. It will be noticed for example on inspection of Figure 5, that the guest key is too short to in anywise affect the tumbler pin 37 and the parts associated therewith. Such is the case also with the usual master key.

Assuming now that an authorized person desires to operate the shut-out and make the usual guest or change key and the usual master key ineffective, the procedure is as follows: Key 43 is now inserted and the bit at its cam end lifts pin 37 to the position shown in Figure 6 at which time the upper face of the duplex pin tumbler is flush with the surface 9' and the shut-out block is thus in break position with respect to the bar, the bar, however, still being locked by the pin 44. Key 43 is now turned clockwise, looking at the face of the lock, which shifts the shut-out block into the position shown in Figure 9 and Figures 3 and 4. The key is then turned to neutral position and withdrawn whereupon the duplex pin tumbler and the pin 44 sink, keeping the bar 9 and the shut-out block in locked position with the cylinder and each other. In the position of the shut-out block shown in Figures 9, 3 and 4, it will be seen that the part 20' is in the path of movement of the pin 30, thereby limiting the rotary movement that may be imparted to the key plug and the roll back arm. It is now impossible for either the guest key or the master key to be used to open the lock. Neither can the lock itself be removed from its casing. Key 42 cannot be inserted for the reason that when the cam end thereof comes against the pin 37, the latter cannot be elevated since the part 23 of the

duplex pin tumbler is out of registry and cannot move upwardly (see Figure 9).

To recondition the lock for use by either the guest key or the master key or the key 42, the operator reinserts key 43 which brings the top surface of the duplex pin tumbler flush with the surface 9', i. e., to break position of the shut-out block. The shut-out block may now be moved back to the position shown in Figure 1 or in Figure 8, the key brought back to neutral and withdrawn. The locking bar is still engaged in the recess 8' and the lock cannot be removed but, since part 20' is again out of the path of movement of the pin 30, the guest key or the master key may be operated as well as the key 42, because once more the duplex pin tumbler has been brought into registry with the holes 12 and 13. If it is desired to remove the lock the key 42 is used to retract the bar 9.

It will be seen that the means for securing the lock against unauthorized removal and the shut-out means are very simple in construction and operation and the cost of the same is partly offset by the elimination of the usual screw bolt for screwing the lock in place against unauthorized removal. This simple construction avoids the necessity of a second set of tumbler chambers and associated parts in one previous form of shut-out mechanism (see Patent No. 1,190,686) or the more familiar arrangement of rotatable rings or sleeves (see for example No. 1,170,481 to Coney).

With respect to the operation of the shut-out block and particularly the movement of the shut-out block to position by the key 43, the following is to be observed. It might be thought that the key after having been operated to move the parts to the position shown in Figure 9, would return the shut-out block as the key is being reversed in rotation to bring it to neutral position. It is to be noted, however, that the lower end of the pin 44 is just slightly below the top of the shut-out block and operates as a detent for the locking block until shortly after the reverse movement has begun to be imparted to the key. Once the key is in motion with respect to the duplex pin tumbler, it will continue its motion without frictionally carrying the shut-out block back from its operative position. Likewise, the same conditions exist when turning the key 43 clockwise to withdraw after it has been used to shift the shut-out block to inoperative position.

Referring now to Figures 14 and 15, I have therein illustrated the application of the locking bar to a lock of the rotatable sleeve type. In this construction, when the special key 51 is inserted, the tumblers are brought to break position insofar as the sleeve 48 and the cylinder 5a are concerned but the sleeve 48 is locked with respect to the key plug 23a. Thereby, when the key 51 is turned, the sleeve 48 rotates with the key plug and through the medium of the pin 37a fitting into the recess 38a in the locking bar 9a, the locking bar is operated either to its protracted or retracted position. In this case, the cylinder is provided with a groove 8a to receive the locking bar 9a. As before the key plug has a keyway 39a and a ledge 49a. The customary roll back arm is shown at 27a. The cylinder has the usual tumbler chambers 31a, tumbler pins 32a and springs 33a; the key plug also has its usual chambers 35a, pins 36a and balls 34a. The sleeve has corresponding chambers.

It will be noted that because of the compact disposition of the parts they can be applied to standard types of lock cylinders of standard 75

lengths. It will also be understood that my improvements may be readily applied to other forms of locks.

I claim:

- 5 1. In a lock, the combination with the rotatable key plug and its latch operating means, of a slide-
able locking bar adapted in its protracted position to engage with an adjacent part to prevent removal of the lock, means associated with the plug to be key-actuated to effect movement of the locking bar when the plug is rotated, and a slide-
able shut-out member movable into and out of the path of movement of the latch operating means and movable independently of the locking bar.
- 10 2. In a lock, the combination with the rotatable key plug and its latch operating means, of a slide-
able locking bar adapted in its protracted position to engage with an adjacent part to prevent removal of the lock, means associated with the plug to be key-actuated to effect movement of the locking bar when the plug is rotated, and a slide-
able shut-out member movable into and out of the path of movement of the latch operating means and movable independently of the locking bar, the same means which effect movement of the locking bar effecting movement of the shut-out member.
- 15 3. In a lock, the combination with the rotatable key plug and its latch operating means, of a slide-
able locking bar adapted in its protracted position to engage with an adjacent part to prevent removal of the lock, means associated with the plug to be key actuated to effect movement of the locking bar when the plug is rotated, and a slide-
able shut-out member movable into and out of the path of movement of the latch operating means, said shut-out member being housed in the locking bar and capable of lost motion with respect thereto.
- 20 4. In a lock, the combination with the rotatable key plug and its latch operating means, of a slide-
able locking bar adapted in its protracted position to engage with an adjacent part to prevent removal of the lock, means associated with the plug to be key-actuated to effect movement of the locking bar when the plug is rotated, and a slide-
able shut-out member movable into and out of the path of movement of the latch operating means, said shut-out member being housed in the locking bar and capable of lost motion with respect thereto, and being operated by the same means which effect movement of the locking bar.
- 25 5. In a lock, the combination with the rotatable key plug and its latch operating means, of a slide-
able locking bar adapted in its protracted position to engage with an adjacent part to prevent removal of the lock, means associated with the plug to be key-actuated to effect movement of the locking bar when the plug is rotated, a slide-
able shut-out member movable into and out of the path of movement of the latch operating means, said shut-out member being housed in the locking bar and capable of lost motion with respect thereto, said bar and shut-out member each having a duplex tumbler pin chamber adapted to be brought into and out of registry, and a duplex tumbler pin normally carried in the shut-out

member adapted to lock the bar and the shut-out member together when key-actuated.

6. In a lock, the combination of a lock cylinder, and a key plug and its latch operating means, of a locking bar slideable in a groove in the lock cylinder, the said lock cylinder being provided with such groove, a shut-out member housed in said bar and slideable with respect thereto and slideable therewith, and tumbler mechanism key-actuated to operate the bar and the shut-out member independently of one another or together.

7. In a lock, the combination of a lock cylinder, and a key plug and its latch operating means, of a locking bar slideable in a groove in the lock cylinder, the said lock cylinder being provided with such groove, a shut-out member housed in said bar and slideable with respect thereto and slideable therewith, and tumbler mechanism key-actuated to operate the bar and the shut-out member independently of one another or together, said tumbler mechanism in certain positions locking the bar to the lock cylinder and the shut-out member to the bar, locking the bar and shut-out member together, and affording a "break" between the bar and said member.

8. In a lock, the combination with the lock cylinder and key plug and its latch operating means, of a slideable shut-out member housed entirely within the cylinder to one side of the plug, and tumbler mechanism adapted to be key-actuated to engage said member to effect movement of the shut-out member when the plug is turned.

9. In a lock, the combination with a lock cylinder and a key plug and its latch operating means, of a slideable locking bar, a shut-out member housed in said bar and slideable with respect thereto and slideable therewith, and a duplex tumbler pin housed within said shut-out member, said locking bar having a duplex tumbler receiving chamber, said tumbler pin being movable in said duplex chamber when the duplex chamber and the duplex pin are brought into registry.

10. In a lock, the combination of a lock cylinder, a key plug and its latch operating means, a slideable locking bar carried in the cylinder to one side of the key plug, a shut-out member slideable in said bar, a tumbler adapted to lock the shut-out member and the bar with respect to the cylinder and each other, and another tumbler key-actuated to render said first tumbler ineffective to lock the shut-out member, said first tumbler projecting slightly into the shut-out member to act as a temporary detent when a key is inserted for actuation of the shut-out member.

11. In a pin-tumbler lock, a pin tumbler cylinder having a screw-threaded outer surface, a lock case adapted to be mounted within a closure and provided with a screw threaded opening into which said cylinder is threaded and a slot in communication with said opening, a dog mounted in said cylinder for movement transversely thereof and adapted to be projected into and retracted out of said slot, and key-operated, pin-tumbler controlled means for projecting and retracting said dog into and out of said slot.

H. B. MONINGER.
